UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

DESIGN FOR A FRAME MEMBER FOR AUTOMATIC SPRINKLER-HEADS OR SIMILAR ARTICLES.

55,463.

Specification for Design.

Patented June 15, 1920.

Application filed July 22, 1919. Serial No. 312,581. Term of patent 14 years.

To all whom it may concern:

Be it known that I, JOHN R. HAMILTON, a citizen of the United States, residing in Yonkers, county of Westchester, State of New York, have invented a new, original, and ornamental Design for Frame Members for Automatic Sprinkler-Heads or Similar Articles, of which the following is a specification, reference being had to the accompanying drawing, which forms part of the same and in which—

Figure 1 is an elevation of one of the

frame members for automatic sprinkler heads or similar articles embodying my new design; and

Fig. 2 is a perspective view thereof taken at a somewhat different angle.

What I claim is:

The ornamental design for a frame member for automatic sprinkler heads or similar articles, substantially as shown.

July 19, 1919.

JOHN R. HAMILTON.
